Patented June 30, 1914.

Fig. 1.

UNITED STATES PATENT OFFICE.

CHARLES W. FARIS, OF IOWA FALLS, IOWA.

ROAD-DRAG.

1,102,189.

Specification of Letters Patent. Patented June 30, 1914.

Application filed October 6, 1913. Serial No. 793,957.

To all whom it may concern:

Be it known that I, CHARLES W. FARIS, a citizen of the United States, and resident of Iowa Falls, in the county of Hardin and State of Iowa, have invented a certain new and useful Road-Drag, of which the following is a specification.

The object of my invention is to provide a road drag of simple, durable and inexpensive construction.

More particularly, it is my object to provide a road drag made of flexibly arranged blades, flexibly connected with each other and adapted for dragging the full width of a road at one operation, regardless of inequalities in the surface of the road.

A further object of my invention is to provide a flexible road drag, provided with means for adjusting the dragging parts for crowning the central part of the highway.

A further object is to provide improved means for flexibly and adjustably connecting the sections of a road drag.

A further object of this invention is to provide draw bars supported throughout the major portion of their lengths above the ground and to provide improved means for flexibly connecting thereto drag devices.

My invention consists in certain details, in the construction, combination and arrangement of the various parts of the device, whereby the objects contemplated are attained, as hereinafter more fully set forth, pointed out in my claims and illustrated in the accompanying drawings, in which:

Figure 1 shows a top or plan view of a road drag, embodying my invention. Fig. 2 shows a rear elevation of the same, and Fig. 3 shows a transverse, sectional view through two of the dragging leaves or blades, illustrating the manner in which the successive blades are flexibly connected.

In the accompanying drawings, I have used the reference numeral 10 to indicate generally the draw bars of my improved road drag which are normally arranged with their inner ends spaced somewhat apart from each other and which extend outwardly and forwardly from their inner ends, as shown in Fig. 1. Each of the draw bars 10 is mounted at each end upon a runner 11, arranged longitudinally of the drag. Rotatably mounted in the outer ends of the draw bars 10 are upright pipes or the like 12. Each of the pipes 12 is connected by an elbow 13 with a transverse, horizontal

pipe 14. The inner ends of the pipes 14 are normally spaced from each other. A rod 15 is inserted into both of the pipes 14 for connecting them. At the inner ends of the pipes 14 are openings to receive headed bolts 16 which are selectively received in openings 17 in the rod 15. The rod 15 is provided with a plurality of the openings 17 so that the distance on the transverse line between the forward outer ends of the bars 10 may be varied as desired.

Rotatably mounted in the rear, adjacent ends of the bars 10, are upright pipes 18, each of which is connected by an elbow 19 with a short, transverse, horizontal pipe 20. The pipes 20 receive a cross bar 21 similar in construction to the cross bar 15 and provided with a plurality of openings 22. The pipes 20 are provided at their adjacent ends with openings to receive headed bolts or the like 23, similar in construction to the bolts 16. Rods 24 are extended in a horizontal plane through the bars 10, as shown in Fig. 1, and are screw threaded for a considerable distance. The rods 24 are pivoted to draw rods 26, which extend forwardly in the machine in converging planes and may be pivoted at their forward ends to the ring or the like 27.

It will readily be seen that by varying the position of the nuts 25 on the rods 24, the distance between the ring 27 and the bars 10 may be varied. Secured to the ring 27 are two chains 28 which extend rearwardly. Secured to the forward sides of the inner ends of the bars 10 are coil springs 29 having on their forward ends hooks 30, which may be hooked into different links of the chains 28. By hooking the hooks 30 into different lengths, the tension on the chains 29 may be regulated as desired. Secured to each of the bars 10 is a plurality of dragging leaves or blades 31. The leaves 31 may be mounted in the following manner.

Bolts 32 may be extended through the bars 10. On their rear ends the bolts 32 are formed with eyelets 33. The blades or dragging leaves 31 are preferably arranged behind each draw bar in overlapping, trailing relation, as shown in Fig. 1. For securing the leaves 31 together and to the bars 10, I provide a plurality of fastening devices A, each comprising a shank 34 on one end of which is a downwardly and rearwardly extended hook 35 and the other end of which is screw threaded to receive nuts 36 and 37.

The shanks 34 are so constructed that the main bodies thereof may extend rearwardly in substantially longitudinal lines, the screw-threaded portions of said shanks being bent so that they may extend rearwardly and away from the center of the machine, as shown in Fig. 1. The nuts 36 are screwed on to the screw threaded portions of the shanks 34. Said portions are then inserted through suitable openings in the sleeve 31 and the nuts 37 are then screwed on to the free ends of said screw threaded portions. The nuts 37 are formed with rearwardly extending eyelets 38 to receive the hook members 35. The parts just described are so arranged that the screw threaded portion of the shank 34 of one of the fastening devices A is extended through each leaf 31, near each end thereof, and approximately in the middle thereof from top to bottom.

It will readily be seen that by raising the leaf 31 next to the rear or last leaf of each series, the hook members 35 may be released from the eyelets 38 on the rear side of the raised leaf and the rearward leaf may be detached from the drag. In this way all of the leaves may be readily detached or attached without the use of tools. At the same time there is little probability that the leaves will become detached during use.

It may be noted that the rods 15 and 22 are somewhat smaller in diameter than the interior diameter of the pipes 14 and 20 so that some play is permitted.

In the practical use of my improved road drag any ordinary doubletrees or eveners may be secured to the ring 27. My drag is preferably made of proper size so that the drive way or main traveled portion of the highway may be dragged at once. As the drag is drawn forward propelled by any suitable motive power, it will be noted that the leaves 31 are flexibly mounted with relation to each other and that the drag sections comprising the respective bars 10 and the leaves secured thereto are also flexibly connected with each other. The width of the path covered by the drag may be varied. By spreading the pipes 14 away from each other in the same way, the angles formed by the bars 10 and the drag leaves with relation to the longitudinal axis of the machine and with relation to the path of travel may be varied as desired. By adjusting the rods 15 and 21 in the pipes 14 and 20, the nuts 25 and the hooks 30 may be adjusted to correspond with the adjustment of the rods just mentioned. By adjusting the hooks 30 the tension on the springs 29 may be regulated.

It will readily be seen that dirt will be carried toward the center of the path dragged and the width of the strip thus crowned may be varied by adjusting the drag. The drag leaves are flexibly mounted in such a way that they will readily pass

over inequalities in the ground. By the use of the chains 28 and the springs 29 the drag sections are held in approximately the proper position at all times and at the same time I am able to secure a maximum flexibility of the sections with relation to each other and to the leaves of each section.

It will readily be seen that if the right hand section of the drag should encounter obstacles and be held back, the tension on the right hand spring 29 will be increased and the tendency will be to draw the right hand section back to its normal position.

It will readily be seen that the leaves may be attached or detached without the use of tools, as desired, and that as many of said leaves and as many series thereof as may be desired may be used.

The adjacent leaves of the two sections of the drag are arranged to extend slightly beyond the ends of the draw bars toward the median lines of the drag so that if desired the inner ends of the draw bars 10 may be brought together and the whole of the way dragged by the leaves 31. The rods 15 and 21 are preferably of somewhat resilient material to form increased flexibility of the drag.

It will be noted that by repeatedly dragging my flexible device over the highway, it will tend to produce a smooth crowned road. On account of the fact that one side of the highway is higher than the other, the drag leaves on that side will tend to cut more deeply than on the low side. The pipes 14 and 20 and the rods 15 and 21 are high enough above the ground to clear obstructions. It may be mentioned that on account of the fact that the hooks enter the eyelets 38 the nuts 37 cannot become unscrewed from the fastening devices.

It will be readily seen that some changes may be made in the details of the construction of my device without departing from its essential features and it is my intention to cover by this application any such changes which may be included within the scope of the appended claims.

Reference is here made to my copending application Serial No. 716,418.

I claim as my invention:

1. A drag comprising a pair of draw bars normally arranged at an obtuse angle with relation to each other, and extending forwardly and outwardly from their inner, adjacent ends, means for adjustably and pivotally securing the forward ends of the draw bars together, means for adjustably and pivotally securing the rearward ends of the draw bars together, draft rods secured to the respective draw bars and pivotally connected at their forward ends, and means for yieldingly securing the forward ends of said draft rods to the rear ends of said draw bars.

2. In a device of the class described, a pair of draw bars in spaced angular relation to each other, means for varying the angularity of said draw bars and for varying their spaced relation, draft rods, means for adjustably securing said draft rods to said draw bars, and a plurality of drag leaves flexibly connected with each of said draw bars.
- 10 3. In a device of the class described, a draw bar, a plurality of drag leaves arranged in overlapped, trailing relation to each other behind said draw bar, and means for securing said leaves to the draw bar and to each other, comprising bolts secured to the draw bar, and fastening devices, each comprising a shank having a downwardly and rearwardly extending hook formed on its forward end, a screw threaded portion at its other end bent at an obtuse angle to the body of the fastening device, said screw threaded portions being inserted through said leaves, a nut on said screw threaded portion having an eyelet formed thereon,
- 15 the respective hooks being received in the eyelet in front of them.
4. In a device of the class described, a pair of draw bars in spaced angular relation to each other, adjustable means for pivotally connecting the forward ends of the draw bars with each other, said means being raised above the draw bars to clear obstructions, adjustable means for pivotally connecting the rearward inner ends of the draw bars with each other, said means being raised to clear obstructions passing between the inner ends of said draw bars, draft rods, means for adjustably connecting said draft rods with said draw bars, yielding devices for connecting the inner ends of the draw bars with the forward ends of the draft rods, said means including devices for varying the tension of said yielding devices.
- 20 Des Moines, Iowa, September 24, 1913.
- CHARLES W. FARIS.
